CUFFER AND STRETCHER DEVICE

Ora Leo Newton, Kansas City, Mo.

Application October 16, 1957, Serial No. 690,539

4 Claims. (Cl. 223—2)

This invention relates to a cuffer and stretcher device adapted for the preparation of steam pressing a cuff, under tension, of a trouser-leg into a fixed peripheral size, consistent with the peripheral size of the trouser-leg, the size of the cuff remaining after the cuffer and stretcher device is removed.

Heretofore new trousers were made and pressed with long trouser legs without cuffs, the cuffs were formed and pressed after a person was measured by a tailor. The trousers were often pressed again after cuffs were formed thereon to press the cuffs. The cuffs and trousers were merely manually positioned on a table or presser buck when newly fabricated or after the cleaning process thereof. Often a cuff was unintentionally made a different peripheral size from the peripheral size of the leg, the cuff being either too small or too large in peripheral measurement thereof for the peripheral size of the leg, thus making an offset between the trouser-leg and the cuff which is often objectionable. The off-set between the cuff and trouser-leg is often caused by thickness of materials, defective tailoring, or by shrinkage due to a cleaning process.

An object of my invention is to provide a cuffer and stretcher device for stretching and holding a cuff of a trouser-leg under tension to a desired peripheral size, consistent with the peripheral size of the trouser-leg, for pressing the cuff to fix the peripheral size consistent with the size of the trouser-leg.

Another object of the present invention is to provide a pair of thin flat metal strips normally spaced parallel with opposed thin edges, means constructed and arranged to reduce the space between the opposed thin edges, the thin flat metal strips adapted for the insertion thereof into a trouser-leg and cuff, means to increase the spacing between the pair of thin flat metal strips adapted to stretch the cuff to a peripheral size consistent with the peripheral size of the trouser-leg, whereby the trouser-leg cuff may be pressed while stretched on the pair of thin flat metal strips to fix the stretched cuff to size.

Another object of the present invention is to provide the thin flat metal strips as arranged in the preceding paragraph except with extended like portions to the thin flat metal strips in a reverse direction with respect to the cuffer and stretcher device. When the trouser-leg is in an opposite position relative to the cuffer and stretcher, the thin flat metal strips of the U-shape are adapted to be inserted into a trouser-leg and only the cuff may be pressed in a pressing machine thus eliminate pressing the trousers again after the cuff is formed.

With these objects in view the invention will be more fully understood from the accompanying drawings, this specification, and the scope of the claims appended.

In the drawings:

Figure 1 is a normal plan view of the cuffer and stretcher device with the thin flat metal strips inserted in, and illustrated stretching, a trouser-leg portion with a cuff.

Figure 2 is an end view of Figure 1.

Figure 3 is a longitudinal edge view of a modified form of cuffer and stretcher device with the substitution of a toggle and hand lever, for changing the spacing of the thin flat metal strips instead of a spring.

5 Figure 4 is a normal plan view of Figure 3.

Figure 5 is a longitudinal view in elevation of a second modification of my cuffer and stretcher device.

Figure 6 is an end view in elevation of Figure 5, illustrating a base provided for supporting the frame of the stretching elements, and the frame is illustrated linked to the base support, to manually change the position and angle of the thin flat metal strips, relative to the press portions illustrated with dash lines. The thin flat metal strips are illustrated with the reverse portions adapted to be inserted in a trouser-leg with a cuff and permit the main portion of the trousers to extend free from the press while the cuff is being pressed. The trouser-leg position with cuff is illustrated with dash lines.

Figure 7 is an end view of a thin flat metal strip covered 20 with cloth for pressing.

Figure 8 is a normal plan view of one thin flat metal strip with an extended reverse portion or U-shape. The companion or opposed thin flat metal strip is made opposite hand to the one illustrated in Figure 8.

25 My simplest form of cuffer and stretcher device is illustrated in Figures 1 and 2. The frame 10 is preferably of a U-shape and comprises the transverse frame members 11 and 12 spaced parallel with the elongated portion 13. Guide rods 14 are spaced parallel from the 30 elongated portion 13 and have their end portions 15 secured in the transverse members 11 and 12.

A slide member 16 is provided with spaced holes 17 therethrough adapted to slide on guide rods 14, and is located parallel with the transverse frame members 11 35 and 12.

The slide member 16 has a lug 18 extended from the slide member 16 and is adapted to hold one end portion 19 of one thin flat metal strip 20 by means of screws 21. A finger control portion 22 is extended from the lug 18 40 toward and adapted to move beyond the free end of the transverse frame member 11, and is adapted to be manually pushed to move the slide member 16 on guide members 14 against the resistance of compression spring 23.

45 The compression spring 23 is located on one of the guide rods 14 between the slide member 16 and a nut 24. The nut 24 is threaded on the rod 14 for adjustment of the compression spring 23.

A stationary thin flat metal strip 25 has one end portion 26 thereof secured to a lug 27 by means of 50 screws 28. The lug 27 is extended from one end of the transverse frame member 12.

The thin flat metal strips 20 and 25 have the same length and are spaced parallel with opposed thin edges relative to the width thereof. The lengths of both thin flat metal strips 20 and 25 are sufficient to be extended into a trouser-leg 29 and extend beyond the cuff 30 on the trouser-leg 29. The compression spring 23 stretches the material of the cuff 20 and trouser-leg 29 and the stretch thereof is manually controlled by a slight pressure on the free end of the finger control portion 26.

A second compression leaf type spring 31 is illustrated with one end thereof connected to slide member 16 by a screw or pin 32 and the opposite end thereof connected to transverse frame member 12 by screw or pin 33. Both springs 23 and 31 may be used to work together or either spring may be omitted when desired in favor of the other spring.

70 Figures 3 and 4 are given the same like numerals of like parts as applied to Figures 1 and 2 for quick identification of the cuffer and stretcher parts, the main difference being a toggle member 34 and lever 35 to replace the

springs 23 and 31 of Figures 1 and 2 for a means of movement of the slide member 16 on guide rods 14. The toggle member 34 is hinged to slide member 16 and transverse members 12 at 36 and 37 respectively.

Figures 5 and 6 illustrate a similar type cuffer and stretcher loosely hinged to the upright members 38 spaced parallel for attachment of the transverse frame members 39 and 40. The upright members 38 have the lower ends thereof secured to a base plate 41. The hinges preferably consist of a bar 42 having one end portion of each pivoted on a respective screw 43 located on a respective upright member 38. The opposite end portion of the bar 42 is pivoted on a respective screw 44 located in the respective transverse frame member 39 or 40. The transverse members 39 and 40 of Figures 5 and 6 are similar to and perform the same functions as transverse members 11 and 12 of Figure 1. Likewise guide rods 45 are similar to guide rods 14. Slide member 46 is similar to slide member 16, compression spring 47 is similar to compression spring 23, nut 48 is similar to nut 24 and frame member 39 is similar to frame member 13.

In Figures 5 and 6 the thin metal flat strips 50 and 51 have one end portion of each secured flatwise to the slide member and transverse member respectively by screws 52. The main portions of the thin metal flat strips 50 and 51 are preferably bent to a normal horizontal position as indicated by dash lines in Figure 6. The thin flat metal strips 50 and 51 have the same function to enter a trouser-leg and cuff as the thin flat metal strips 20 and 25.

The thin flat metal strips 50 and 51 have thin flat metal strips 54 and 55 extended in a reverse position therefrom to form an U shape with sufficient space between each thin flat metal strip and the extension thereof to allow the trouser-leg material to pass therebetween. This arrangement permits a trouser-leg to be mounted on the thin flat metal strips from either side of the cuffer and stretcher device.

The reverse portions 54 and 55 of the thin flat metal strips permits a small portion of a trouser-leg and cuff to be entered in the pressing machine 56 as illustrated in dash lines, the main portion of the trousers being free of the press for pressing the cuff only.

What I claim as new, and desire to secure by Letters Patent, is:

1. A cuffer and stretcher device comprising: a rigid bar bent to a U shape having an elongated base portion with transverse end portions spaced parallel, a pair of guide rods having equivalent lengths of the base portion of said rigid bar, said pair of guide rods spaced parallel with the base portion of said rigid bar, said pair of guide rods having all of the ends thereof secured to said transverse end portions of said rigid bar, a slideable bar, said slideable bar located parallel with the transverse end portions of said rigid bar and having holes therethrough mounted on said pair of guide rods, a pair of thin flat metal strips relative to a section of said rigid bar, said pair of thin flat metal strips being spaced parallel with opposed thin edges, one of the thin flat metal strips having one end portion thereof attached to said slideable bar, the other thin flat metal strip having one end portion thereof attached to one end portion of said rigid bar, a compression spring, said compression spring being located and confined on one of said guide rods to normally hold said slideable bar against the transverse bar portion having the free end of said rigid bar so as to give the maximum of spacing between said pair of thin flat metal strips, said slideable bar adapted to be manually moved against said compression spring to narrow the spacing between said thin flat metal strips so that the pair of thin flat metal strips are adapted to be inserted into a cuff and leg portion of a pair of trousers, and said compression spring adapted to force said slideable bar toward the transverse portion having the free end of said rigid bar so as to

equally stretch the cuff and leg portion of the pair of trousers.

2. A cuffer and stretcher device comprising: a U-shaped rigid bar having an elongated base portion with transverse end portions spaced parallel, a pair of guide rods having equivalent lengths of the base portion of said U-shaped rigid bar, said pair of guide rods spaced parallel with the base portion of said U-shaped rigid bar, said pair of guide rods having the ends thereof secured to both transverse end portions of said U-shaped rigid bar, a slideable bar, said slideable bar having holes therethrough mounted on said pair of guide rods; a pair of thin flat metal strips, relative to a section of said rigid bar; said pair of thin flat metal strips being spaced parallel with opposed thin edges, one thin flat metal strip having one end portion detachably attached to said slideable bar, the other thin flat metal strip having one end portion detachably attached to one end portion of said U-shaped rigid bar, a spring, said spring located to normally hold said slideable bar against the transverse bar portion having the free end of the U-shaped rigid bar so as to give the maximum of spacing between said pair of thin flat metal strips, said slideable bar adapted to be manually moved against said spring to narrow the spacing between said thin flat metal strips so that the pair of thin flat metal strips are adapted to be inserted into a cuff and leg portion of a pair of trousers, and said spring adapted to force said slideable bar toward the transverse portion having the free end of said U-shaped rigid bar so as to equally stretch the cuff and leg portion of the pair of trousers.

3. A cuffer and stretcher device comprising: a U-shaped rigid bar having an elongated base portion with transverse end portions spaced parallel, a pair of guide rods having equivalent lengths of the base portion of said U-shaped rigid bar, said pair of guide rods spaced parallel with the base portion of said U-shaped rigid bar, said pair of guide rods having the ends thereof secured to the transverse end portions of said U-shaped rigid bar, a transverse bar, said transverse bar having holes therethrough slideably mounted on said pair of guide rods; a pair of thin flat metal strips, relative to a section of said U-shaped bar; said pair of thin flat metal strips being spaced parallel with opposed thin edges, one thin flat metal strip having one end portion attached to said transverse bar, the other thin flat metal strip having one end portion attached to one end portion of said U-shaped rigid bar, a compression spring, said compression spring mounted on one of said pair of spaced guide rods, said compression spring being located to normally hold said transverse bar against the transverse bar portion having the free end of said U-shaped rigid bar so as to give the maximum of spacing between the pair of thin flat metal strips, said transverse bar adapted to be manually moved against said compression spring to narrow the spacing between said thin flat metal strips so that the pair of thin flat metal strips are adapted to be inserted into a cuff and leg portion of a pair of trousers, and said compression spring adapted to force said slideable bar toward the transverse portion having the free end of the U-shaped rigid bar so as to equally stretch the cuff and leg portion of the pair of trousers.

4. A cuffer and stretcher device as claimed in claim 3, a second pair of thin flat metal strips, said second pair of thin flat metal strips being extended from the projected ends of said first mentioned pair of thin flat metal strips with reverse curves and spaced parallel in the same plane therewith.
